UNITED STATES PATENT OFFICE.

CICERO LA HATTE, OF VICKSBURG, MISSISSIPPI.

DESIGN FOR A STORE FRONT OR SIMILAR ARTICLE.

Application filed December 9, 1926. Serial No. 20,000. Term of patent 7 years.

To all whom it may concern:

Be it known that I, CICERO LA HATTE, a citizen of the United States, residing at Vicksburg, in the county of Warren and State of Mississippi, have invented a new, original, and ornamental Design for a Store Front or Similar Article, of which the following is a specification, reference being had to the accompanying drawing, forming part thereof.

The figure is a perspective view of a store front or similar article showing my new design.

I claim:

The ornamental design for a store front or similar article as shown.

CICERO LA HATTE.
